DIGITAL-DISPLAY ELECTRONIC WRISTWATCH

Jean-Samuel Wuhl, Geneva, Switzerland, assignor to
Bulova Watch Co., Inc., New York, N.Y.

Filed Aug. 15, 1974, Ser. No. 497,762

Term of patent 14 years

Int. Cl. D10—02

U.S. Cl. D10—38

Fig. 1.

FIG. 1 is a top perspective view of a digital-display electronic wristwatch showing my new design;

FIG. 2 is a right side elevational view thereof, the left side being a mirror image thereto;

FIG. 3 is a top plan view thereof;

FIG. 4 is a bottom plan view thereof;

FIG. 5 is a left end elevational view thereof, the right end being substantially a mirror image thereto without a crown;

FIG. 6 is a right side elevational view thereof in the open position.

I claim:

The ornamental design for a digital-display electronic wristwatch, substantially as shown and described.
